PATENTED SEPT. 18, 1906.

A. RIPPERGER.

APPARATUS FOR THE THERAPEUTIC USE OF RADIANT ENERGY.

APPLICATION FILED MAY 24, 1905.

UNITED STATES PATENT OFFICE.

ALBERT RIPPERGER, OF NEW YORK, N. Y.

APPARATUS FOR THE THERAPEUTIC USE OF RADIANT ENERGY.

No. 831,103.

Specification of Letters Patent.

Patented Sept. 18, 1906.

Application filed May 24, 1905. Serial No. 262,026.

To all whom it may concern:

Be it known that I, ALBERT RIPPERGER, a citizen of the United States, residing in the city, county, and State of New York, have 5 invented a new and useful Improvement in Apparatus for the Therapeutic Use of Radiant Energy, of which the following is a specification.

My invention is an apparatus for the therapeutic use of radiant energy; and it consists in means whereby to effectively apply the rays at the place and over the area desired, protecting both patient and others from the undesired influence of such rays. To this 15 end I inclose the source of radiant energy, whatever it may be, in an impervious casing—that is, impervious to said rays—having an opening through which rays of only the desired extent may be passed, and I provide means for such a support and adjustment of the casing that the rays may be 20 readily directed to the area where they are to operate, as fully set forth hereinafter and as illustrated in the accompanying drawings, in 25 which—

Figure 1 is a perspective view of my improved apparatus. Fig. 2 is a view of the clamp; Fig. 3, an enlarged section through the impervious shield or casing; Fig. 4, a perspective view of the casing detached and provided with an adjustable mirror; Figs. 5 and 30 6, diagrammatic views illustrating the position of the source of energy, casing, physician, and patient in the use of the apparatus, 35 the letter P indicating the position of the patient and P' that of the physician.

In carrying out my invention I may use what is known as an "X-ray tube," illustrated in the drawings; but as my apparatus 40 may be used in connection with different sources of radiant energy I show the X-ray tube only as an illustration of any of the various sources which may be employed, whether tubes or cases receiving electric currents or containing radium or otherwise. 45 These I designate under the term "source of radiant energy D." This source of radiant energy I inclose within a shield C, having one or more openings x, through which the rays 50 may pass to the person to be treated. As shown, the said shield is in the form of a casing closed so as to prevent the passage of rays except in one direction, and in order that it may be light, cheap, and a bad conductor of electricity I prefer to form it of

wood or other material which is a non-conductor of electricity, and I coat this on the outside with a coating of composition of rubber and oxid of lead and coat the inside, preferably, with a number of coatings of a composition of celluloid varnish and bismuth oxid, which coating in comparatively thin layers is impervious to radiant rays and is a practically perfect non-conductor.

In order to vary the dimensions of the 65 opening, one or more of the sides of the casing may consist of a series of sections p p, fitting one within the other and capable of being detached, and, as shown, both the top and bottom sides of the casing are removable 70 and resting upon supports or ledges q, thus permitting either or both sides to be closed or opened.

When the source of energy is an X-ray tube or other source requiring an electric current, 75 the tube may be supported by one of the detachable sides (as shown, the top) of a casing provided with binder-posts e for making the proper electric connections, and this top part is removable to permit the tube to be carried 80 into and out of the casing. Preferably the tube is adjustably supported within the casing, so as to be set in different positions. As shown, a clamp k is supported by a screw r, which can be raised or lowered by turning a 85 nut u thereon, the said nut resting on the top of the casing through which the screw passes. At the lower end the screw is provided with a transverse socket to receive an arm i, extending from the clamp k, which may be set to 90 different positions and secured by a set-screw h. The clamp k is forked to receive 95 between its fingers one of the necks of the tube, which is clamped in place by means of a screw t.

The casing C is combined with a suitable support A, permitting the said casing to be raised and lowered, turned, and secured in position over a bed or stretcher and shifted in and out, as desired. The support may be of 100 different characters. As shown, it is a base a, provided with a standard b and a cross bar or arm d, to which the casing is secured at the outer end. Preferably the casing is connected with the bar d either at the top and bottom or other sides of the casing, so as to permit the latter to be set upon the arm in different positions. Thus the end of the bar may be secured to the outer ring C or section 105 of the top or bottom of the casing, which 110

therefore can be turned to any desired position. Preferably a carrier *B* slides upon the standard *b* and has a transverse socket to receive the bar or arm *d*, which may be adjusted longitudinally. The vertical and horizontal adjustments may be effected by means of hand-wheels *ff* on shafts provided with pinions engaging racks in the standard and arm or otherwise.

10 To one side of the casing an arm *v* is secured by a ball-and-socket joint, and to the outer end of this arm is secured by a ball-and-socket joint a mirror *o*, which can be secured in any desired position to reflect a reduced 15 picture of the shield and tube or other source of energy therein. In order that the tube may be watched during the operation, I have shown the casing as also cut away at one side, leaving an opening *w*, which is desirable in 20 some cases, as where a long X-ray tube may project beyond the casing. This opening is so placed that neither the operator nor the patient is exposed to the rays.

In Fig. 1 I have shown an opening at one 25 side of the casing having guides 2' for receiving a slide 3, having an opening *l* for the passage of rays which may be used in combination with the detachable top and bottom sections or as a substitute therefor, the apparatus being provided with a plurality of slides 30 having openings of different sizes.

To secure additional adjustment, the

standard *b* may rotate in the socket in the base.

Without limiting myself to the precise construction and arrangement of parts shown, I claim as my invention—

1. The combination with the source of radiant energy and surrounding impervious casing, having an opening, of a mirror and 35 support connecting it adjustably with the casing, substantially as set forth.

2. An apparatus of the character described having a support for the source of radiant energy and a surrounding shield having a 40 coating containing bismuth, substantially as 45 described.

3. In an apparatus of the character described for the therapeutic use of radiant energy, the combination of a cylindrical shield, 50 openings formed in said cylindrical shield, a plurality of detachable sections within said cylindrical shield, openings in the top, bottom and sides of said cylindrical shield, and removably-secured covers or doors for said 55 openings, for the purpose specified.

In testimony whereof I have signed my name to this specification in the presence of two subscribing witnesses.

ALBERT RIPPERGER.
